UNITED STATES PATENT OFFICE

JEROME E. BAUM, OF NEW YORK, N. Y.

DESIGN FOR A PAPER ROLL CONTAINER

Application filed June 10, 1931. Serial No. 40,162. Term of patent 7 years.

To all whom it may concern:

Be it known that I, JEROME E. BAUM, a citizen of the United States, residing at New York city, county of New York, borough of Manhattan and State of New York, have invented a new, original, and ornamental Design for a Paper Roll Container, of which the following is a specification, reference being had to the accompanying drawings, forming a part thereof.

Figure 1 is a top view of a paper roll container showing my new design.

Figure 2 is a side view of Figure 1.

Figure 3 is an end view of Figure 1.

I claim:—

The ornamental design for a paper roll container as shown.

JEROME E. BAUM.
